FINGER RING

Robert Willner, 2 Cherry Lane, Bristol, R.I. 02809

Filed Feb. 1, 1971, Ser. No. 111,796

Term of patent 14 years

Int. Cl. D11—01

U.S. Cl. D45—10

FIG. 1

FIG. 2

FIG. 3

FIG. 4

FIG. 1 is a front elevational view of a finger ring showing my new design, the back thereof being identical in appearance;

FIG. 2 is a side elevational view thereof;

FIG. 3 is a top plan view thereof; and

FIG. 4 is a bottom plan view thereof.

I claim:

The ornamental design for a finger ring, substantially as shown and described.
